HOIST FOR DUMP TRUCK BODIES

Roland Deré, Quebec, Quebec, Canada

Application December 18, 1948, Serial No. 66,046
In Canada November 10, 1947

4 Claims. (Cl. 298—22)

1

The present invention relates to a hoist and, more specifically, to a hydraulically-operated hoist for dump-truck bodies.

A characteristic of such hoists is that the body or box of the truck is pivotally raised by cylinder-and-piston means connected between the body and the chassis. When the box is in lowered position resting on the chassis, the cylinder and piston are disposed underneath the former with their axes substantially parallel to the bottom thereof. With the hydraulically-operated members thus ineffectively disposed, a tremendous starting thrust is required in the system in order to displace the box upward. Such mechanisms may even become jammed under unusually heavy loads.

The problem set forth above has long been recognized, but it has been found difficult to arrange a hoist effectively in the limited space available beneath a truck body. In consequence, most attempts to improve truck-dumping mechanisms have been centered upon the connection between hoist and body. Thus it has been found that an improved mechanism is obtained when the body and chassis are connected by two or more pivoted links, and the latter actuated by piston means with, or without, the aid of a crank. Unfortunately this elaborates and increases the cost of the machinery, and such systems still require excessively high starting pressure in the hydraulic system.

The present invention seeks to solve the problem in a much simpler and more effective manner than that suggested above. Thus it is the principle of the invention that, at the moment of raising the body from a resting position, a piston-actuated crank brings into play a lever which directly lifts the body upward. When the latter has been raised somewhat, the cylinder-and-piston means, whose axis is now disposed at an effective angle relative to the bottom of the body, carry the dumping operation to completion.

The main object, then, of the present invention is to provide a hoist for dump-trucks which does not require excessively high starting thrust in order to raise the body from the chassis.

Moreover, another important object resides in the provision of a hoist of the character described which is simple in construction and economical to manufacture.

And another object is to provide a hoist as set forth above which is light, yet durable in operation.

Other objects and advantages will become apparent or be further pointed out in the description to follow.

As an example, and for purposes of illustration

2

only, a preferred embodiment of my invention is shown in the annexed drawings, wherein:

Figure 1 shows a perspective view of the body and part of the chassis of a dump truck, the former maintained in raised position by the hoist of this invention;

Fig. 2 shows a detail perspective view of the lever and crank mechanism of the hoist;

Fig. 3 shows a plan view of the hoist;

Fig. 4 shows an elevation along the line 4—4 in Fig. 3 with the body in lowered position, and

Fig. 5 shows a corresponding elevation view with the body in partially-raised position.

Referring now to the drawings, wherein the same reference characters denote corresponding parts throughout, the hoist of the invention is seen to be associated with the body B and the chassis C of a truck, and consists mainly of the cylinder 20, piston 21, and the crank-and-lever members 22.

The essential parts of a typical body and truck chassis are indicated in the drawings in order to aid in understanding the operation of the invention. Thus Fig. 1 shows that the box of the body is supported and strengthened by the longitudinal stringers 6 which are in turn supplemented to the channels 7. Secured to these channels near the rear of the body are the pivot-blocks 8 which are pivoted in any suitable sockets disposed on the chassis supports. The chassis is provided with a pair of channels 9 upon which channels 7 are adapted to rest when the body is lowered into normal position. The channels 9, in turn, are secured to and bedded on the sleepers or stringers 10 of the chassis, and will have the usual transverse, reinforcing angle-bars such as 11 welded across the stringers. For the purpose of this invention, two longitudinal supporting bars such as 12 will be disposed between angle-bars 11 inside channels 9, and will have welded thereto the supporting frames 13 near the forward ends thereof. The frames 13 will act as bearings in which the crank-and-lever mechanism will be pivotally mounted, as hereinafter described.

Piston 21 is slidable in cylinder 20, and is actuated by the hydraulic pressure in the latter. A system for controlling the displacement of the piston is shown in Figs. 4 and 5 where a pump 23 is powered by the transmission of the truck through shaft 24, and feeds oil through lines 25 and 26 into either end of the cylinder. The pump may be controlled by any suitable means through the line 27. The free end of the piston is pivotally secured to the base of the body as at 28, substantially near the middle of the latter.

At the opposite end to the piston, cylinder 21

is pivotally connected to the crank-and-lever mechanism of the hoist. Since this mechanism is in turn pivoted to supports on the chassis, any displacement of the piston causes a corresponding displacement of the body together with, or independent of, the lever mechanism.

Figs. 2 and 3 best show the dispositions of cylinder, crank and lever relative to the chassis supports. Thus the chassis frames 13 are provided, near the forward ends thereof, with integral, lateral collars or sleeves 14. These collars act as bearings for a shaft 29 which extends transverse the chassis above and between channels 9.

Inside each frame 13, a short crank-arm 30 is keyed to shaft 29. The free ends of each of these crank arms are connected by a pin 31 and the adjacent end of cylinder 20 is rotatably mounted on this pin. Hence any axial displacement of the cylinder will actuate the crank mechanism and cause rotation of shaft 29.

Keyed to each end of the shaft 29 outside frames 13 are the lever arms 32. These arms are substantially longer than the crank arms and are adapted to raise the body of the truck when shaft 29 is angularly displaced. Projecting inwardly from each reinforcing channel of the body will be disposed a roller 33 adapted to rest on lever arm 32. This arrangement will reduce friction during upward displacement of the body.

The operation of the hoist is as follows:

When the body of the truck is at rest on the chassis, the piston will be disposed mostly inside the cylinder; both these members being secured between the crank mechanism and the body with their axes very nearly parallel to the bottom of the latter in the limited space therebeneath. The crank mechanisms arms, however, are disposed at an effective angle to the cylinder axis, and so, upon introduction of pressure into the system, the cylinder is driven against the crank and causes shaft 29 to pivot. The lever arms 32 are hence pivoted upward, as between Figs. 4 and 5, and carry with them the body of the truck.

When the crank has been displaced to some extent by the cylinder, the latter comes into contact with shaft 29 and causes a binding of the crank and lever system. However, at this point the lever arms have reached their highest point, and have raised the body to an angle where the piston and cylinder are effectively disposed to complete the dumping operation.

Obviously, from the foregoing, the present invention fulfills the objectives hereinbefore set forth. Whilst avoiding the introduction of expensive and weighty systems of connected links between body and chassis, nonetheless this invention solves the problem of effectively disposing a simple hoist in the limited space below the body of a truck. The hoist described reduces greatly the hydraulic pressure required to start the dumping operation, yet is of such a nature as to not increase the effective weight of the body in any way. The simple parts of constituting this hoist, few of which require accurate machining, may be cheaply and easily assembled and are utilized in such a way as to be durable in operation.

It will be understood that I do not limit myself to the particular embodiment of my invention

herein shown and described, but that various changes in the size, shape and arrangement of parts may be resorted to without departing from the spirit of the invention or the scope of the subjoined claims.

Having thus described my invention, I claim:

1. The combination with a dump truck having a chassis, a body pivotally mounted thereon and hydraulically-operated cylinder-and-piston means connected at one end to said body and adapted to raise the latter from the chassis, of means for aiding in the initiation of upward displacement of the body comprising a shaft rotatably journaled transverse the chassis, lever arms keyed to said shaft adapted to engage the bottom of the body during the first portion of the upward displacement thereof, and a crank keyed to said shaft and pivotally secured to the free end of said cylinder-and-piston means.
- 10 2. A hoist for dump trucks having a body and chassis, said hoist adapted to raise said body from said chassis and comprising: lever means pivotally mounted on said chassis engageable with the bottom of said body, and hydraulically-operated cylinder-and-piston means connected between said lever means and said body, whereby elongation of said cylinder-and-piston means causes, firstly, a pivoting of said lever means to displace said body upwardly somewhat, and secondly, a direct upward displacement of said body.
- 15 3. In a dump truck having a body and a chassis, a hoist adapted to raise the former from the latter and comprising: a crank and a lever movable together and pivotally mounted on said chassis, said lever engageable with the bottom of said body, and hydraulically-operated cylinder-and-piston means connected between said crank and said body whereby elongation of said means causes firstly a pivoting of said crank and lever to raise the body somewhat and secondly causes direct upward displacement of said body.

4. In combination with a dump-truck having a body and chassis, a hoist adapted to raise the former from the latter and comprising: a transverse shaft rotatably journaled in said chassis, lever arms keyed to said shaft engagable from the bottom of said body, a crank keyed to said shaft, a cylinder and a piston co-operable therewith connected between said crank and said body, and hydraulic means for displacing said piston in said cylinder; whereby displacement of said piston out of said cylinder causes, firstly, a pivoting of said crank shaft, and lever to move said body upwardly a predetermined amount, and secondly, direct upward displacement of said body.

ROLAND DORÉ.
